(57) CLAIM

The ornamental design for a combined decorative cat and heart decoration, as shown and described.

DESCRIPTION

FIG. 1 is a perspective view of a combined decorative cat and heart decoration showing my new design;

FIG. 2 is a front view thereof;

FIG. 3 is a right side elevational view thereof;

FIG. 4 is a left side elevational view thereof;

FIG. 5 is a top elevational view thereof;

FIG. 6 is a bottom elevational view thereof; and,

FIG. 7 is a perspective view of my prototype visor showing my new design.

It being understood that the broken lines are for illustrative purposes only and form no part of the claimed design.
